US00D976859S

(12) **United States Design Patent** (10) **Patent No.:** **US D976,859 S**
(45) **Date of Patent:** **** Jan. 31, 2023**

(54) **MOBILE PHONE**

(71) Applicant: **VIVO MOBILE COMMUNICATION CO., LTD.**, Guangdong (CN)

(72) Inventor: **Junhao Lin**, Guangdong (CN)

(73) Assignee: **VIVO MOBILE COMMUNICATION CO., LTD.**, Guangdong (CN)

(**) Term: **15 Years**

(21) Appl. No.: **29/733,017**

(22) Filed: **Apr. 29, 2020**

(30) **Foreign Application Priority Data**

Oct. 31, 2019 (CN) 201930598898.0

(51) **LOC (14) Cl.** **14-03**

(57) **CLAIM**

The ornamental design for a mobile phone, as shown and described.

DESCRIPTION

FIG. 1 is a rear perspective view of a mobile phone showing the present invention;

FIG. 2 is a front view of the invention illustrated in FIG. 1; FIG. 3 is a front perspective view of the invention illustrated in FIG. 1;

FIG. 4 is a rear view of the invention illustrated in FIG. 1; FIG. 5 is a top plan view of the invention illustrated in FIG. 1;

FIG. 6 is a bottom plan view of the invention illustrated in FIG. 1;

FIG. 7 is a right side view of the invention illustrated in FIG. 1; and,

FIG. 8 is a left side view of the invention illustrated in FIG. 1.

1 Claim, 7 Drawing Sheets
